CRYPTOGRAPHIC MACHINE

Beue Tann, Washington, D. C.

Application May 5, 1943, Serial No. 485,781

23 Claims. (Cl. 35—3)

My invention relates to a cryptographic machine, and has particular reference to a cryptographic machine for coding and decoding messages or other intelligence, by means of which an exceedingly great number of messages or the like may be coded and decoded without repetition of any particular code setting, thus insuring the secrecy of the message or the like and rendering it practically impossible to decode the message or the like without the use of a similar machine and without a prior knowledge of the code setting of the machine.

It is an object of my invention to provide a cryptographic machine including a fixed set of letters, characters, figures, words, signs or symbols which may constitute the elements of the clear text, and a movable set or sets of letters, characters, figures, words, signs or symbols which may constitute the elements of the code or cipher text, and to provide a novel and efficient means for successively and progressively moving one set or sets of the text elements with respect to the other set or sets in a great number of different combinations or relationships to thus avoid repetition of the coded and decoded message or of parts thereof, to effectively maintain the secrecy of successive messages.

It is an object of my present invention to provide a cryptographic machine in which a fixed set of letters or other indicia has associated therewith a movable set or sets of letters or other indicia and in which the positions or relationships between the movable set or sets may be successively and progressively varied with respect to the fixed set, by determining the extent of movement imparted to the movable set or sets by an operating member which controls and effects the operation of the movable set or sets with respect to the fixed set of letters or other indicia.

It is an object of my invention to provide a cryptographic machine in which a set of letters or other indicia is fixed with respect to the casing of the machine and has associated therewith a movable set of letters or other indicia which with said fixed set may constitute the elements of the clear text, and to associate with the elements of the clear text a set or sets of letters or other indicia which are movable with respect to the elements of the clear text and which may constitute the elements of the code or cipher text, and to provide a novel and efficient means for successively and progressively varying the extent of movement of the movable set or sets with respect to the fixed set whereby an exceedingly great number of relationships may be obtained

between the fixed and movable sets of the elements of the clear and code or cipher text.

It is an object of my invention to provide a cryptographic machine of the character above mentioned in which the movement of the movable set or sets of letters or other indicia is effected by suitable pawl-and-ratchet mechanism actuated by an oscillating member which, in turn, is under the control of the operator of the machine, and to provide a novel means by which the extent of movement of the oscillating member is successively and progressively varied to vary the extent of movement imparted by the pawl-and-ratchet mechanism to the movable set or sets of letters or other indicia.

It is a still further object of my invention to provide a cryptographic machine of the character above mentioned in which the movement of the oscillating member, and hence, the movement of the movable set or sets of letters or other indicia, is determined by the position of a rotary member having variously-spaced stop surfaces or shoulders thereon adapted to be engaged by the oscillating member during the operation of the machine, the position of these stop surfaces or shoulders being successively and progressively varied during the coding and decoding operations to thus vary the extent of movement imparted to the movable set or sets of letters or other indicia.

It is a still further object of my invention to provide a cryptographic machine of the character above mentioned in which the various component parts of the machine may be assembled and associated in an almost infinite number of relative positions to thereby vary, to a very great extent, the relationship existing between the sets of fixed and movable letters or other indicia.

In the accompanying drawings forming a part of my present application, and wherein, for the purpose of illustration, I have shown several preferred embodiments of my invention,

Figure 1 is a plan view of the cryptographic machine of my present invention,

Figs. 2, 3, 4, 5 and 6 are plan views of separate disc-like members adapted for assembly on a common shaft and which, when assembled, constitute an important element of my present invention,

Fig. 7 is a plan view of the assembled disc-like members shown in Figs. 2 to 6 inclusive,

Fig. 8 is a vertical sectional view on the line 8—8 of Fig. 1,

Fig. 9 is a fragmentary plan view of the cryptographic machine shown in Fig. 1, with the top or cover member of the machine removed and

certain portions broken away in order to show the underlying mechanism.

Fig. 10 is a vertical sectional view on the line 10—10 of Fig. 9.

Fig. 11 is a plan view of a modified form of my invention.

Fig. 12 is a vertical sectional view on the line 12—12 of Fig. 11.

Figs. 13 and 14 are plan views of separate disc-like members adapted for assembly on a common shaft and which, when assembled, constitute an important element of that form of my invention shown in Figs. 11 and 12.

Fig. 15 is a fragmentary plan view of a further modified form of my present invention.

Fig. 16 is a side elevation of that form of my invention shown in Fig. 15, and

Figs. 17, 18, 19, 20 and 21 are plan views of separate disc-like members adapted for assembly on a common shaft and which, when assembled, constitute an important element of that form of my invention shown in Figs. 15 and 16.

Referring to the drawings wherein like reference numerals have been used to designate like parts throughout the several views, the numeral 1 designates broadly the casing or housing of the machine, which casing or housing includes a base 2, upstanding side walls 3 and 4, a curved end wall 5, a platform 6, and a cover or top 7. The particular shape and construction of the casing or housing 1 is relatively unimportant and forms no part of my present invention. The cover or top 7 is provided with a semi-circular cut-out portion or window 8, and projecting inwardly from the curved wall defining said semi-circular cut-out portion are a plurality of substantially rectangular, relatively thin, spaced tabs 9, preferably thirteen in number, and each inscribed with a letter of the alphabet. These tabs 9, as shown in Fig. 1, are inscribed with the letters B, D, F, H, J, L, N, P, R, T, V, X and Z, i. e., with progressively alternate letters of the alphabet beginning with B and ending with Z.

A vertical shaft 10 is journalled for rotation in a bearing 11 secured to the base 2 and has its upper end extending through an aperture in the platform 6, which upper end terminates in the plane of the cover or top 7 at a point approximately at the center of the semi-circular cut-out portion or window 8. Keyed or otherwise secured to the shaft 10 for rotation therewith is a ratchet wheel 12, the upper surface of which, as viewed in Figs. 8 and 10, is disposed in parallel spaced relation below the under surface of the platform 6. A lever arm 13 is positioned between the ratchet wheel 12 and the underside of the platform 6 and has its inner end mounted for pivotal movement about the shaft 10 and its outer end provided with an upstanding lug or abutment 14 adapted to extend through, and to terminate above, an arcuate slot 15 cut through the platform 6. Intermediate the ends of the lever arm 13 and pivotally mounted on the underside thereof is a pawl 16, to the outer or free end of which is attached a tension spring 17 which tends to maintain the pawl in contact with the teeth on the periphery of the ratchet wheel 12 but which permits the lever arm 13 to move in a clockwise direction as viewed in Fig. 9, without affecting the position of the ratchet wheel 12. A spring-actuated pivoted pawl 18 is mounted on the underside of the platform 6, this pawl permitting counterclockwise rotation of the ratchet wheel 12 but preventing clockwise rotation thereof. When the lever arm 13 is oscillated about

the shaft 10 by mechanism to be hereinafter described, the pawl 16 mounted on the said lever arm will cause the ratchet wheel 12 and shaft 10 to rotate in a counter-clockwise direction when the said lever arm is moved in a counter-clockwise direction, during which movement the pawl 18 in no way interferes with the rotation of the ratchet wheel 12. A tension spring 19 extends between the lever arm 13 and a fixed point on the underside of the platform 6, this spring serving to maintain said arm against a fixed stop 20 which depends from the underside of the platform 6. A second fixed stop 21 also depends from the underside of the said platform, the distance 10 between the stops 20 and 21 being such that for each counter-clockwise movement of the lever arm 13, said arm moves only for a sufficient distance to cause the ratchet wheel 12 to move a distance equivalent to the spacing between adjacent teeth on the periphery of said ratchet wheel.

Immediately above the platform 6 is a disc 22 having a radial arm 23 and a second radial arm 24, this disc being pivotally mounted on the shaft 10. The arm 23 overlies the arcuate slot 15 and during its oscillation in a counterclockwise direction as viewed in Fig. 9, is adapted to contact the abutment 14 on the lever arm 13 to effect a step-by-step rotation of the ratchet wheel 12. The outer or free end portion of the arm 24 is bent downwardly to provide a depending portion 25, the purpose of which will be hereinafter described. A pawl 26 is pivotally mounted on arm 23 and is resiliently urged in a counter-clockwise direction by a tension spring 27 which extends 25 between said pawl and a fixed point on the disc 22. A pair of spaced, spring pressed pawls 28 and 29 are mounted on the upper surface of the platform 6, the springs associated with said pawls tending to urge them in a counter-clockwise direction about their pivotal mountings.

Immediately above the disc 22 is a ratchet wheel 30 provided with a circular series of holes 31. This ratchet wheel is preferably provided with a total of fifty-one teeth about its periphery, 45 it being noted that one of the teeth, i. e., the tooth 32, is of double length. Preferably, there are fifty-two holes 31 in the circular series of holes in the ratchet wheel 30. This ratchet wheel 30 is apertured at its center and is mounted on the shaft 10 for free rotation thereon immediately above the disc 22. When thus mounted, the pawls 26, 28 and 29 engage the teeth on the periphery of the wheel 30, it being obvious that oscillation of the disc 22 and its associated arm 23 in a counter-clockwise direction, will cause a step-by-step rotation of the ratchet wheel 30 and that the spring-pressed pawls 28 and 29, while permitting such rotation, will prevent clockwise rotation of said ratchet wheel.

Superimposed upon the ratchet wheel 30 is a thin, flat disc 33 of greater diameter than said ratchet wheel, said disc having at its center an aperture through which the shaft 10 extends. This disc 33 is provided with one or more apertures located at a point or points remote from the center of said disc and overlying the circular series of holes 31 in the underlying ratchet wheel, and a pin 34 is passed through each aperture in the disc 33 and enters one of the holes 31 in the ratchet wheel 30, whereby the said disc is caused to rotate with said ratchet wheel about the shaft 10. The upper face of the disc 33 is inscribed with two concentric rows of letters 35 and 36, there being, preferably, fifty-two letters in each concentric row. The outermost row 35 has alter-

nate spaces 31 inscribed with the letters A, C, E, G, I, K, M, O, Q, S, U, W, Y, A, C, E, G, I, K, M, O, Q, S, U, W and Y, i. e., with progressively alternate letters of two alphabets each beginning with A and ending with Y. The alternate spaces 38 intermediate the alternate spaces 31 above referred to, are inscribed with the letters Q, S, K, M, E, Y, G, I, C, W, A, O, U, Q, S, K, M, E, Y, G, I, C, W, A, O and U, i. e., with two similar series of thirteen letters each. The innermost row 36 has alternate spaces 39 inscribed with the letters N, O, P, Q, R, S, T, U, V, W, X, Y, Z, N, O, P, Q, R, S, T, U, V, W, X, Y and Z, i. e., with two similar series of thirteen letters each beginning with N and ending with Z. The alternate spaces 40 intermediate the alternate spaces 39 above referred to, are inscribed with the letters Z, X, V, N, Y, O, Q, P, S, T, R, U, W, Z, X, V, N, Y, O, Q, P, S, T, R, U and W, i. e., with two similar series of thirteen letters each.

Mounted above the disc 33 is a thin, flat disc 41 of a diameter corresponding to the inner diameter of the innermost row 36 of letters inscribed on the upper face of the disc 33, the disc 41 having at its center an aperture through which the upper end of the shaft 10 extends. The disc 41 is keyed or otherwise secured to the shaft 10 so as to rotate therewith. Extending radially from the periphery of the disc 41 are a plurality of spaced tabs 42, preferably twenty-six in number, these tabs being inscribed with the letters A, B, D, C, F, E, G, H, I, J, K, L, M, A, B, D, C, F, E, G, H, I, J, K, L and M, i. e., with two similar series of thirteen letters each.

As a convenient means for effecting manual operation of the machine of my present invention, I provide an operating lever 43 having at its forward, free end a key 43' by means of which the said lever may be manually depressed. The inner end of the lever 43 is mounted on a horizontal pivot 44 which extends between, and is secured to, a pair of upstanding lugs 45 mounted on the base 2. A tension spring 46 extends between the lever 43 and a fixed point on the inner surface of the side wall 3 and tends to maintain the lever 43 in its normal position shown in Fig. 8. A bell crank lever 47 having a relatively long arm 48 and a relatively short arm 49 is pivotally mounted on the base 2 by means of a suitable bracket 50 rigidly secured to said base. A rod or link 51 extends between the upper free end of the arm 48 and the arm 23 of the disc 22 whereby oscillation of the bell crank lever 47 will impart oscillation to the disc 22 and to the parts carried thereby. As a convenient means for imparting oscillatory movements to the bell crank lever 47, the said lever is connected to the lever 43 by means of a pivoted link 52, so that as the lever 43 is moved downwardly the bell crank lever 47 will be rocked in a counterclockwise direction as viewed in Fig. 8, and, through the rod or link 51, will impart a like movement to the lever arm 23 and its associated disc 22, it being obvious that as the lever 43 is released the tension spring 46 will return the said lever to the normal position and that such movement of the said lever, through the link 52, will rock the bell crank lever 47 in a clockwise direction as viewed in Fig. 8.

An important feature of my present invention resides in means whereby the extent of the oscillatory movement imparted to the disc 22 by the operating lever 43 is successively and progressively varied. In the form of my invention shown in Figs. 1 to 10, inclusive, I mount a shaft 53 between spaced, upstanding brackets 54 and 55 se-

cured to the base 2. Upon the shaft 53, I mount a ratchet wheel 56, this ratchet wheel preferably having an odd number of teeth, say nineteen. Adjacent this ratchet wheel 56, I mount on the shaft 53 an indicating wheel 57, having a series of consecutive numbers arranged on its periphery and corresponding to the number of teeth on the ratchet wheel 56. As shown in Figs. 7 and 9 the numbers on the periphery of the disc or wheel 57 run consecutively from one to nineteen, as there are nineteen teeth on the ratchet wheel 56. I next mount on the shaft 53 three discs 58, 59 and 60, the detailed construction of these discs being shown, respectively, in Figs. 2, 3 and 5 of the accompanying drawings. Each of these discs is provided with a centrally-located aperture of a diameter slightly exceeding the diameter of the shaft 53 and the periphery of each disc is provided with segmental cut-out portions of varying lengths to form variously spaced and variously dimensioned stop surfaces or shoulders 61 of segmental configuration. Each of the discs 58, 59 and 60 is provided with a circular series of holes 62, each series corresponding in number to the number of teeth on the ratchet wheel 56, i. e., in the present instance, there is a total of nineteen holes in each of the series in each of the three discs. The ratchet wheel 56 and the indicating wheel or disc 57 are each provided with an aperture located a distance from their respective centers corresponding to the radius of the circular series of holes 62 in the discs 58, 59 and 60. After the ratchet wheel 56, the indicating wheel or disc 57 and the three discs 58, 59 and 60 are mounted on the shaft 53, a pin 63 is passed through the aligned holes in the ratchet wheel and indicating wheel and through one of the holes 62 in each of the discs 58, 59 and 60 so that these five members are moved together as a unit for simultaneous rotation on the shaft 53. I next mount on the shaft 53 a second indicating wheel or disc 64 having a series of consecutive numbers arranged on its periphery and adjacent this wheel or disc 64 I mount on the shaft 53 a second ratchet wheel 65, this ratchet wheel 65 having an odd number of teeth, say fifteen, in which instance the series of numbers on the periphery of the wheel or disc 64 will run consecutively from one to fifteen. The wheel or disc 64 and ratchet wheel 65 are secured together for simultaneous rotation on the shaft 53 by means of a pin 66 which passes through said wheel or disc and ratchet wheel, it being understood that the group comprising members 56, 57, 58, 59 and 60 and the group comprising members 64 and 65 are capable of independent rotation on the stationary shaft 53. Disc 64, like discs 58, 59 and 60, is provided with segmental cut-out portions to provide peripherally-spaced stop surfaces or shoulders 61 of segmental configuration, the series of numbers above referred to being applied to said stop surfaces or shoulders and to the exposed surfaces between said stop surfaces or shoulders.

In order to effect rotation of the members 56, 57, 58, 59 and 60 on the shaft 53, I mount on said shaft immediately adjacent the ratchet wheel 56 an upstanding arm 67 having its lower apertured end pivotally mounted on said shaft and having a pawl 68 pivotally mounted on its side near its upper or free end in a position to overlie the ratchet wheel 56. A tension spring 69 connects one end of said pawl to a fixed point on said arm, which spring tends at all times to urge the opposite end of said pawl into engagement with the teeth on the periphery of the

ratchet wheel 56. A second, spring-pressed pawl 70 is mounted on a fixed part of the casing and has one end engaging the teeth of the ratchet wheel 56 and its opposite end connected by a tension spring 71 to a fixed point on the casing, the arrangement being such that the pawl 70 will permit clockwise rotation of the ratchet wheel 56 and the members secured thereto for rotation on the shaft 53 but will prevent counter-clockwise rotation of said ratchet wheel and its associated members.

In order to effect rotation of the members 64 and 65 on the shaft 53 independently of the rotation of the ratchet wheel 56 and the members secured thereto, I mount on said shaft immediately adjacent the ratchet wheel 65 an upstanding arm 72 having its lower apertured end pivotally mounted on said shaft and having a pawl 73 pivotally mounted on its side near its upper or free end in a position to overlie the ratchet wheel 65. A tension spring 74 connects one end of said pawl to a fixed point on said arm, which spring tends at all times to urge the opposite end of said pawl into engagement with the teeth on the periphery of the ratchet wheel 65. A second, spring-pressed pawl 75 is mounted on a fixed part of the casing and has one end engaging the teeth of the ratchet wheel 65 and its opposite end connected by a suitable tension spring to a fixed point on the casing, the arrangement being such that the pawl 75 will permit clockwise rotation of the ratchet wheel 65 and its connected indicating wheel or disc 64 but will prevent counter-clockwise rotation of said ratchet wheel and indicating wheel or disc.

As a convenient means for effecting actuation of the pawls 68 and 73 to effect a progressive, step-by-step rotation of the ratchet wheels 56 and 65 and their associated parts on the shaft 53, I connect the upper or free end of the arm 67 by means of a rod or link 76, to the upper or free end of an upstanding lever arm 77 keyed or otherwise fixed on a shaft 78, which shaft is journaled for rotation in spaced, upstanding brackets 79 and 80 secured to the base 2 of the machine near the front thereof, and I connect the upper or free end of the arm 72 by means of a rod or link 81, to the upper or free end of an upstanding lever arm 82 keyed or otherwise fixed on the shaft 78. I key or otherwise fixedly secure to the end of the shaft 78, a lever arm 83 which extends substantially horizontally of the machine and substantially at right angles with respect to the upstanding lever arms 77 and 82, the lever arm 83 having a pin or abutment 84 extending laterally from its outer or free end and located in the path of the operating lever 43, the arrangement being such that as the said operating lever approaches its lowermost position, it will contact the pin or abutment 84 and will force the outer or free end of the lever arm 83 downwardly, thus causing a clockwise movement of the shaft 78 as viewed in Fig. 8, and, through the lever arms 77 and 82 and the rods or links 76 and 81, causing a corresponding movement of the arms 67 and 72 and of the pawls 68 and 73 carried thereby, which results in the ratchet wheels 56 and 65 and their associated parts being moved a distance equivalent to the spacing between each of the teeth on the periphery of the respective ratchet wheels.

In the modified form of my invention shown in Figs. 11 to 14 inclusive, the construction and operation of certain of the parts included therein is substantially the same as that shown and

- described in connection with that form of my invention shown in Figs. 1 to 10 inclusive, except insofar as relates to the mechanism for varying the extent of movement or oscillation of the disc 22 and its associated parts. In Figs. 1 to 10, inclusive, the means for determining the extent of oscillation of the disc 22 is mounted on a horizontal shaft, which construction necessitates the provision of a casing having a substantial height. 10 In the modified form of my invention shown in Figs. 11 to 14, inclusive, the means for determining the extent of oscillation of the disc 22 is relatively flat and is mounted on a relatively short, vertical shaft so that it is possible to make the machine relatively flat and to enclose the same in a relatively shallow casing, thus greatly reducing the size of the machine. The means for imparting step-by-step rotation to the ratchet wheel 12, movement of the disc 22 and its associated arms 23 and 24, step-by-step rotation of the ratchet wheel 30, and rotation of the lettered discs 33 and 41 with respect to the series of fixed, lettered tabs 9, may be the same as those shown and described in connection with Figs. 1 to 10, 15 inclusive, a showing of such means having been omitted from Figs. 11 and 12 for the sake of simplicity and clearness of illustration, it being noted, however, that in the form of my invention shown in Figs. 11 and 12, I have omitted the operating lever 42, bell crank lever 47 and link 51, and that the lever arm 23 is extended through an arcuate slot 85 cut through the upper edge of the curved end wall 5 of the casing. The extended lever arm 23 has connected thereto a tension 20 spring 86, the opposite end of which is connected to a fixed point on the side wall 3 of the casing, this spring urging said lever arm in a clockwise direction as viewed in Fig. 11. 25 As a means for determining the extent of oscillation of the lever arm 23 and its associated parts, I mount on the base 2 of the casing a stationary, vertical shaft 87 preferably of "stepped" formation as shown in Fig. 12. This shaft may be conveniently secured to the base 2 by means of 30 a bolt 88 which passes through an aperture in said base and threads into the lower end of said shaft. The shaft 87 has a threaded upper end 89 which passes through an aperture in the inner end of a bar or bracket 90 secured to the side wall 4 of the casing, a nut 91 being threaded on the upper end of said shaft and above the said bar or bracket. Arranged upon the shaft 87 is a radially extending arm or lever 92 on the outer end of which is a spring-pressed pawl 55 (not shown) which engages the teeth on a ratchet wheel 93 also mounted on said shaft. The arm 92, the pawl carried by said arm, and the ratchet wheel 93, correspond, respectively, in function and operation, to the arm 72, pawl 73 and ratchet wheel 65 previously described, the ratchet wheel 93 having an odd number of teeth, say 15, on its periphery. A spring-pressed pawl 94 is mounted on the base 2 of the casing and functions to prevent clockwise rotation of the ratchet wheel 93 as viewed in Fig. 11. A disc 95 is mounted on shaft 87 immediately above the ratchet wheel 93 and is provided on its upper face with a series of numerals ranging from one to seventeen as indicated in Fig. 11. A relatively thin spacing disc 96 is mounted on shaft 87 immediately above disc 95, and above said spacing disc is mounted on said shaft a disc 97, the shape and configuration of which is best shown in Figs. 11 and 14, it being noted that this disc is provided with segmental cut-out portions to

provide peripherally-spaced stop surfaces or shoulders 98. A pin 99 is passed through aligned openings in the ratchet wheel 93, disc 95, spacing disc 96 and disc 97 so that these members rotate about the shaft 87 as a unit, oscillation of the arm 92 and engagement of its spring-pressed pawl with the teeth on the ratchet wheel 93 effecting such rotation.

A disc 100 is next mounted on the shaft 87, the shape and configuration of which is best shown in Fig. 13, it being noted that this disc is provided with a series of segmental cut-out portions of varying lengths and depths to form variously-spaced and variously-dimensioned stop surfaces or shoulders 101 of segmental configuration. The disc 100 is provided with a circular series of holes 102, preferably nineteen holes comprising the series. Above the disc 100 and on the shaft 87 there is next mounted a relatively thin disc 103 on the upper surface of which is arranged a series of numerals varying from one to nineteen as shown in Fig. 11. A ratchet wheel 104 is next mounted on the shaft 87, this ratchet wheel having a total of nineteen teeth on its periphery, which teeth are engaged by a spring-pressed pawl 105 carried by an arm 106, the inner end of which is mounted for oscillation on shaft 87 immediately below the arm or bracket 90. A pin 107 is passed through the ratchet wheel 104, disc 103 and through any one of the holes 102 in disc 100 so that these members rotate about the shaft 87 as a unit, oscillation of the arm 106 and engagement of the pawl 105 effecting such rotation. A spring-pressed pawl 108 is mounted on the underside of the arm or bracket 90 and functions to prevent clockwise rotation of the ratchet wheel 104 as viewed in Fig. 11. The arm 106, the pawl 105, and the ratchet wheel 104, correspond, respectively, in function and operation, to the arm 67, pawl 68 and ratchet wheel 56 previously described.

As a convenient means for effecting progressive, step-by-step rotation of the ratchet wheels 93 and 104 and their associated parts about the shaft 87, I connect the outer end of the arm 106, by means of a rod or link 109, to the outer end of a lever arm 110 keyed on a vertical shaft 111 journaled for rotation in a suitable bearing (not shown) mounted on the base 2 near the side 3 of the casing. A lever arm 112 is also keyed on shaft 111 and is disposed at an angle of approximately 90 degrees with respect to arm 110, this lever arm 112 having at its outer end an apertured lug 113 which slidably engages a rod or link 114, one end of which is connected to the arm 23, it being noted that the outer end of said rod or link is provided with an enlarged end portion 115 for a purpose to be hereinafter described. A second arm (not shown) corresponding structurally to the arm 110, is also keyed on shaft 111 at the approximate level of the arm 92 and is connected to the outer end of the arm 92 by means of a rod or link (not shown) corresponding structurally to the rod or link 109. In order to limit the clockwise movement of the arms 110 keyed on the shaft 111 as said arms move from the dotted line position shown in Fig. 11 to the full line position shown therein, I mount a stop 116 on the base 2 of the casing in a position to be contacted by the arm 110 which moves immediately above said base and which is connected to the arm 92, a suitable tension spring (not shown) being connected to the lowermost of the arms 110 and to a fixed point on the base 2 to resiliently urge said arm into contact

with said stop. It will be understood, of course, that as the lever arm 23 shown in Fig. 11 is moved in a counterclockwise direction as viewed in said figure, it contacts, during the latter part of such movement and prior to its contact with the end of the slot 85, an abutment 14 carried by an arm 13, and moves said arm 13 in a counterclockwise direction and, through a pawl 16, causes a progressive, step-by-step rotation of a ratchet wheel 12 and of a disc 40, all of these parts being adequately disclosed and described in connection with that form of my invention shown in Figs. 1 to 10, inclusive.

In Figs. 15 to 21, inclusive, I have shown a further modification of my present invention, numerous of the parts of which correspond in construction, function and operation to the forms of my invention previously shown and described, particularly the form shown and described in connection with Figs. 11 and 12. This form of modification comprises a vertical shaft 87' extending upwardly from the base 2 of the casing and secured thereto, and having mounted thereon, in the order named, an arm 92'; a ratchet 93' which, like the ratchet 93 has, say, seventeen teeth on its periphery; a disc 95' provided on its upper face with a series of numerals ranging from one to seventeen as indicated in Fig. 15; a relatively thin spacing disc 96'; and a disc 97', the shape and configuration of which is best shown in Figs. 15 and 20, it being noted that this disc is provided with segmental cut-out portions to provide peripherally-spaced stop surfaces or shoulders 98'. A pin (not shown, but corresponding to the pin 99 shown in Fig. 12) is passed through aligned apertures in the ratchet wheel 93', disc 95', spacing disc 96' and disc 97' so that these members rotate about the shaft 87' as a unit, oscillation of the arm 92' being effected by means corresponding to the means disclosed in Fig. 12 for effecting progressive, step-by-step rotation of the ratchet wheel 93, disc 95, spacing disc 96 and disc 97. I next mount on the shaft 87', in the order named, discs 117, 118, 119 and 120, the shape and configuration of which are shown, respectively, in Figs. 18, 21, 19 and 17, it being noted that the discs 117, 118 and 119 are of progressively decreasing diameter and that these three discs are each provided with a series of segmental cut-out portions of varying lengths and depths to form variously-spaced and variously dimensioned stop surfaces or shoulders 121, 122 and 123, respectively, and that each of the discs 117, 118 and 119 is provided with a circular series of nineteen holes 124, 125 and 126, respectively. The disc 120 is provided with a hole 127 adapted to be aligned with selected holes of the underlying series of holes 126, 125 and 124 in the discs 119, 118 and 117, respectively, this disc 120 having arranged on its upper face, a circular series of numerals ranging from one to nineteen. I next mount on the shaft 87' a ratchet wheel 104', this ratchet wheel having a total of nineteen teeth on its periphery, which teeth are engaged by a spring-pressed pawl 105' carried by an arm 106', the inner end of which arm is mounted for oscillation on shaft 87' immediately below the arm or bracket 90'. A nut 91' is threaded on the upper end of the shaft 87 immediately above the arm or bracket 90'. A pin (not shown but corresponding to the pin 107 shown in Fig. 12) is passed through a hole in the ratchet wheel 104', through hole 127, and through one of the holes 78 in each circular series of holes 126, 125 and 124

in discs 112, 113 and 117, respectively, so that these members rotate about the shaft 87' as a unit, oscillation of the arm 106' and engagement of the pawl 105' with the teeth on the ratchet wheel 104' effecting such rotation. The arm 106' is connected by a rod or link 169' to an arm such as the arm 110 of Fig. 11, it being understood that a similar rod or link (not shown) is connected to the arm 92' and that said rod or link is connected to an arm such as the lowermost arm 110 of Fig. 11, the arrangement being such that the arms 92' and 106' are oscillated to effect a progressive, step-by-step rotation of the ratchets 93' and 104', respectively. Suitable spring-pressed pawls 94' and 108' are mounted on the base 2 and on the underside of arm or bracket 90', respectively, and function to prevent counterclockwise movement of the ratchets 93' and 104', respectively, as viewed in Fig. 15.

Suitable indicating marks, such as the arrows 128 on cover 7 (see Fig. 1), 129 on platform 6 (see Fig. 8), 130 on the edge of the double tooth 32 (see Fig. 8), 131 and 132 on pawls 68 and 73, respectively (see Fig. 9), 133 on base 2 (see Fig. 11), and 134 on base 2 (see Fig. 15), are provided to cooperate with letters or numerals on the peripheries or upper surfaces of certain of the discs in a manner to be hereinafter described.

Having thus described the construction of the several forms of my invention presented herein, I will now describe the manner in which these devices are operable to obtain or accomplish the objects of my present invention. Referring to Figs. 1 to 10, inclusive, I first assemble on the left-hand end of shaft 53, as viewed in Fig. 7 and in the order named, ratchet 56, indicating disc 57, and discs 58, 59 and 60, and then pass pin 63 through the aligned holes in ratchet 56 and disc 57 and through one of the holes in each of the circular series of holes in discs 58, 59 and 60. I next assemble on the right hand end of shaft 53, disc 64, followed by ratchet 65, and then pass pin 66 through the hole in ratchet 65 and through one of the holes of the circular series of holes in disc 64. Shaft 53 and its associated discs and ratchets just described, are now mounted in the machine and occupy the position shown in Figs. 8 and 9. Pawls 68 and 73 engage, respectively, the ratchets 56 and 65, whereby oscillation of the arms 67 and 72 on which said pawls are mounted, will effect progressive, step-by-step rotation of said ratchets and the parts connected thereto, this rotation being of different arcuate increments, due to the fact that the ratchet 56 has nineteen teeth, whereas the ratchet 65 has only fifteen teeth. When thus arranged, it will be obvious that depression of the operating lever 43 will cause said lever to strike the pin 84 on lever arm 83, which will depress arm 83 to cause limited rotation of the shaft 78, which will advance ratchets 56 and 65 a distance equivalent to the spacing of the teeth on said ratchets, this being effected through the medium of upstanding lever arms 77 and 82, rods or links 76 and 81 and pawls 68 and 73. When operating lever 43 is released and is pulled upwardly by spring 46, the shaft 78 and the parts carried thereby will be returned to their normal position by the spring 135 which extends between bracket 54 and an upstanding lever arm 136 keyed on shaft 78, the 70 pawls 70 and 75 preventing reverse rotation of the ratchets 56 and 65 during such return movement.

The disc 22 is placed on the shaft 10 and the arm 23 of said disc is connected to the arm 48 of bell-crank lever 47 by means of rod or link 75

51, it being obvious that as the operating lever 43 is depressed, the connection 52 between said lever and arm 49 of bell-crank lever 47 will cause the arm 23, disc 22 and arm 24 to move in a counterclockwise direction as viewed in Figs. 1 and 9. As the arm 23 approaches the end of its counterclockwise movement with respect to the slot 15, it contacts abutment 14 on lever arm 13 and moves this arm in a counterclockwise direction 10 until said arm abuts the fixed stop 21. During this movement of the lever arm 13 between stops 20 and 21, the pawl 16 carried on said arm and which engages the teeth on ratchet wheel 12, causes a progressive, step-by-step counterclockwise rotation of said ratchet wheel and of the shaft 10 to which said ratchet wheel is keyed or otherwise secured.

By reference to Fig. 9, it will be noted that the depending portion 25 of arm 24 occupies a position where it abuts the inner surface of the indicating disc 57, this position representing the limit of the clockwise movement of said arm 24, the said depending portion 25 having reached this position by passing through the segmental spaces 25 between the radial stop surfaces or shoulders on the discs 64, 60, 59 and 58. When operating lever 43 is depressed, the disc 22 and arms 23 and 24 carried thereby, are moved in a counterclockwise direction, during which movement the depending portion 25 passes through the spaces between the radial stop surfaces or shoulders on the discs 64, 60, 59 and 58 and reaches a position where it overlies the ratchet 65. When this position is reached, the operating lever 43 contacts the pin 35 84 on lever arm 83 and, through upstanding lever arms 77 and 82, rods or links 76 and 81 and pawls 68 and 73, causes the ratchets 56 and 65 and the parts carried thereby to be advanced a distance equivalent to the spacing of the teeth on the respective ratchets, it being noted that the depending portion 25 of lever 24 in no way interferes with this movement, due to the fact that it has been moved to a position beyond the end of the disc 64 and above the ratchet 65. When the operating lever is released, the disc 22 and arms 23 and 24 carried thereby move in a clockwise direction, but the depending portion 25 of arm 24 strikes against one of the stop surfaces or shoulders on one of the discs 58, 59, 60 or 64, which stop surface or shoulder has been moved into the path of said depending portion by the progressive, step-by-step rotation of said discs. Hence, the clockwise or return movement of the disc 22 and its arms 23 and 24 is determined by contact between depending portion 25 and one of the shoulders on the series of discs 58, 59, 60 and 64. Due to the irregular spacing of these stop surfaces or shoulders and the differential rotation of the fifteen-toothed ratchet 65 as compared with the rotation of the nineteen-toothed ratchet 56, it will be obvious that the limit of the clockwise or return movement of disc 22 and its arms 23 and 24 is constantly varied and that such limit determines the extent of the counterclockwise movement imparted to the lever arm 23 and the pawl 26 carried thereby. This means for progressively varying the counterclockwise movement of the arm 23 and its pawl 26, constitutes an important feature of my present invention.

In the form of my invention shown in Figs. 11 to 14 inclusive, the variation of the clockwise or return movement of the lever arm 23 is effected by contact between the depending portion 25 of arm 24 with the stop surfaces or shoulders 98 and 101 on the discs 97 and 100, respectively,

which stop surfaces or shoulders are formed on said discs by the variously-spaced and variously-dimensioned segmental cut-out portions of said discs. As the lever arm 23 of this form of my invention is moved in a counterclockwise direction as viewed in Fig. 11, the disc 22 and arms 23 and 24 are moved to positions shown in dotted lines in said figure and wherein the depending portion 25 is out of the path of movement of the stop surfaces or shoulders 98 on disc 97 whereby said disc and its associated parts may be rotated without interference by the depending portion 25. It will be noted that during the initial counterclockwise movement of the arm 23, the rod or link 114 slides within the apertured lug 113 until the enlarged portion 115 on said rod or link contacts said lug. At this point in the operation of the mechanism the depending portion 25 of arm 24 has been moved to a position represented by dotted lines in Fig. 11. Continued counterclockwise movement of the arm 23 causes said arm to contact abutment 14 to rotate ratchet 12 and shaft 10 a distance equivalent to the distance between the teeth on ratchet 12, and also causes the rod or link 114 to move the arms 110 on shaft 111 in a counterclockwise direction, which movement, through links 109, arms 92 and 106, and pawls 105, causes the ratchets 93 and 104 and the parts carried thereby to be advanced a distance equivalent to the spacing of the teeth on the respective ratchets. When the operating lever 23 is released, the disc 22 and arms 23 and 24 carried thereby move in a clockwise direction, until the depending portion 25 of arm 24 strikes against one of the stop surfaces or shoulders 98 or 101 on the discs 97 and 100, respectively, which stop surface or shoulder has been moved into the path of said depending portion by the progressive, step-by-step rotation imparted to the discs 97 and 100. Hence, the clockwise or return movement of the disc 22 and its arms 23 and 24 is determined by contact between depending portion 25 and one of the shoulders 98 or 101. Due to the irregular spacing of shoulders 98 and 101 and the differential rotation of the seventeen-toothed ratchet 93 as compared with the rotation of the nineteen-toothed ratchet 104, it will be obvious that the limit of the clockwise or return movement of disc 22 and its arms 23 and 24 is constantly varied and that the variously-positioned and variously-dimensioned stop surfaces or shoulders 98 and 101 determine the limit of the clockwise or return movement of disc 22 and its arms 23 and 24 and, hence, determine the extent of the counterclockwise movement imparted to the lever arm 23 and pawl 26 carried thereby. It will be obvious that in this form of my present invention, the disc 97 corresponds in function and operation to the disc 64 of the mechanism shown in Figs. 4, 7 and 9, and that the disc 100 corresponds in function and operation to the combined discs 58, 59 and 60.

In the form of my invention shown in Figs. 15 to 21, inclusive, the disc 97' corresponds in function and operation to the disc 64 and disc 97 previously described. In this form of my invention, however, the variously-positioned and variously-dimensioned stop surfaces or shoulders are not formed on a single disc such as the disc 100 of Fig. 13, but are provided on three separate discs 117, 118 and 119 of progressively decreasing diameter as illustrated in Figs. 18, 21 and 19, respectively. The operation of this modified form of my invention will, it is believed, be obvious from the presently-presented description of

the operation of the mechanism shown in Figs. 11 to 14, inclusive. Suffice it to say that actuation of the lever arm 23 initially moves the depending portion 25 from the position shown in Fig. 15 to a position where said depending portion is out of the path of movement of the stop surfaces or shoulders 98' of disc 97', whereupon arms 106' are given a clockwise movement and, through pawls 105', cause a clockwise rotation of ratchets 93' and 104' and of the parts carried thereby, a distance equivalent to the spacing of teeth on the respective ratchets. When the operating lever 23 is released, the disc 22 and arms 23 and 24 move in a clockwise direction until the depending portion 25 strikes one of the stop surfaces 98', 121, 122 or 123, which stop surfaces or shoulders are successively and to widely varied degrees, moved into the path of the said depending portion to determine the extent of the clockwise or return movement of the disc 22 and its associated parts. Any preferred form of mechanism may be provided between the manually operated lever arm 23 and the arms 106' for transmitting movement from said arm 23 and arms 106 to effect the progressive, step-by-step, differential rotation of the ratchets 93' and 104'.

It will be obvious from the above that it is possible to assemble the discs 58, 59 and 60 to their respective ratchets in an almost infinite number of relationships, due to the presence of the circular series of holes 62 provided in said discs, and that the single disc 100, and the plurality of discs 117, 118 and 119 may likewise be assembled with their respective ratchets 104 and 104'. Hence, the clockwise movement of the disc 22 may be varied to a very great extent by the innumerable ways in which the discs 58, 59 and 60, or the single disc 100, or the discs 117, 118 and 119, are assembled. Further variation is possible by varying the number of teeth, and the relationship between the number of teeth, on the ratchets 56 and 65, 93 and 104, and 93' and 104'.

The ratchet wheel 30 is placed on shaft 10 in a position wherein the indicating arrow 130 on the edge of the double tooth 32 is aligned with the indicating arrow 129 on the platform 6, with pawls 26, 28 and 29 engaging the teeth on the periphery of said ratchet. Disc 33 is now placed on shaft 10 and the pin 34 is inserted through an aperture in said disc and into any one of the holes 31 of the circular series of holes in said disc. Disc 41 is now placed on shaft 10 and is keyed or otherwise secured to said shaft for rotation therewith. Cover 1 is then secured to the top of the casing and occupies the position shown in Fig. 1. When thus assembled, the machine is ready for the coding or decoding of messages or other data.

When it is desired to send a message, the operator, after ascertaining that the indicating mark 130 is in alignment or registration with the indicating mark 129, makes a note of the number on disc 57 which is opposite the indicating mark 131, and a note of the number on disc 64 which is opposite the indicating mark 132, these numbers, in the setting shown in Fig. 9, being "9" and "7," respectively. He then makes a note of the first three letters which are exposed between the first four stationary tabs 9 adjacent the indicating mark 128 on cover 1 and reading in a counterclockwise direction with respect to indicating mark 128, i. e., between the letters "B," "D," "F" and "H," these letters, in the setting shown in Fig. 1, being "K," "M" and "O." He next makes a note of the letter on the series of tabs 42 on disc 41, which letter is radially inward with re-

spect to the tab 9 on which the letter "B" appears, and, which, in the setting shown in Fig. 1, is the letter "H." The code message will therefore start with the key numerals "9" and "7," followed by the key letters "K," "M," "O" and "H," i. e., "97KMOH." Assuming that the message to be coded is "Claims allowed," the operator locates the letter "C" on the series of letters appearing on the outermost series comprising the stationary tabs 9 and the outer series 35 of disc 33, which combined series may constitute the letters of the clear text. It will be noted that the letter "O" appears radially inward of the letter "C," and, hence, "O," which is the code or cipher letter, will constitute the first letter of the actual code message. The lever 43 is then depressed by the operator, which depressing swings the depending portion 25 of lever 24 from its position shown in Fig. 9 to a position clear of the discs 57, 58, 59, 60 and 64, continued movement of the operating lever 43 causing the ratchet wheel 30 and its associated disc 33 to be rotated for a distance corresponding to five of the teeth on said ratchet, and also causing the ratchet 12, shaft 10 and disc 41 to be operated for a distance corresponding to one of the teeth on said ratchet 12. The relationship between the letters of the clear and code or cipher text is therefore materially changed, due to the rotation of the discs 33 and 41 relative to the stationary lettered tabs 9 and relative to each other. Upon the release of lever 43, the disc 22 and its arms 23 and 24 swing in a clockwise direction as viewed in Fig. 9, but this movement is arrested by contact of the depending portion 25 with one of the stop surfaces or shoulders 61 on disc 64. The operator then locates the letter "L" on the clear text series and finds that the code or cipher letter radially inward from this letter is the letter "U" which letter will constitute the second letter of the actual code message. Operating lever 43 is again depressed, which depressing results in the rotation of ratchet 30 and disc 23 a distance corresponding to one of the teeth on said ratchet, and also causes the ratchet 12, shaft 10 and disc 41 to be operated a distance corresponding to one of the teeth on said ratchet 12. This again changes the relationship between the letters of the clear and code or cipher text. Upon the release of the lever 43, the disc 22 and its arms 23 and 24 swing in a clockwise direction as viewed in Fig. 9 until this movement is arrested by contact of the depending portion 25 with one of the stop surfaces 61 on the disc 60. The operator then locates the letter "A" on the clear text series and finds that the corresponding letter on the code or cipher series is "N," which letter will constitute the third letter of the actual code message. Upon next depressing the lever 43, the ratchet 30 will be moved a distance corresponding to three of the teeth on said ratchet, as the return movement of the disc 22 and its arms 23 and 24 had been arrested, as the result of the previous depression of the lever 43, by contact with the stop surface 61 of disc 59. The operation of coding the message is completed by repeated depression of the operating lever 43 and by translating the letters of the actual message from the clear text to the code or cipher text. When such translation is completed for the message "Claims allowed," let it be assumed that the complete coded message will read "97KMOH QUNPMK GJNUBYI."

This code message is transmitted by writing, phone or other means of communication, and when said message is received by an authorized

recipient supplied with a like machine, it is a comparatively easy matter to decode or decipher the message. Assuming that the coding and decoding machines are similarly arranged, i. e., that the corresponding ratchets in the two machines have the same number of teeth, that the discs and ratchets are similarly arranged on shaft 53 and that the discs 33 are similarly arranged on ratchets 39, the recipient of the code message above given by way of example, sets his machine in accordance with the key numerals and letters constituting the initial part of the code message, i. e., he brings the indicating marks 129 and 130 into alignment or registration, and sets the indicating disc 57 so that its number "9" is opposite the indicating mark 131 and the number "7" is opposite the indicating mark 132 on pawls 68 and 73, respectively. He next sets the disc 33 in accordance with the key letters "KMO" contained in the initial portion of the code message, i. e., he arranges the disc 33 so that the letters "K," "M" and "O" appear on the outer circle of letters between the letters "B," "D," "F" and "H" on stationary tabs 9. Finally, he moves the disc 41 until the letter "H" on tabs 42 is arranged radially inward from the indicating mark 128 and the letter "B" on stationary tabs 9. His machine is now set for a simple and accurate decoding or deciphering of the code message. He first refers to the letters of the code or cipher text and locates the letter "O" which appears on the inner series of letters 39. He finds that the letter on the outer series of letters 37 which is radially outward with respect to said letter "O," is the letter "C," and he writes this down as the first letter of the decoded message. He then depresses the operating lever 43 which moves the ratchet 30 and its associated disc 33 and also moves the disc 41, the extent of movement of said disc 33 being a distance corresponding to five of the teeth on said ratchet, and the extent of movement of said disc 41 being a distance corresponding to one of the teeth on the ratchet 12. Hence this first depression of lever 43 during the decoding or deciphering operation corresponds to the first depression of said lever made by the operator of the coding machine during the preparation of the code message in the manner above described, i. e., the letters of the several series will occupy on the recipient's machine, the same identical relation which said letters occupied on the sender's or transmitter's machine at this stage of the coding operation. By locating the letter "U" on the innermost or code series of letters the recipient will readily ascertain that the corresponding letter on the outer or clear text series is "L" and, hence, "L" will constitute the second letter of the decoded message. Lever 43 is again depressed which depressing results in the rotation of ratchets 30 and disc 33 a distance corresponding to one of the teeth on said ratchet and also causes ratchet 12, shaft 10 and disc 41 to be operated a distance corresponding to one of the teeth on said ratchet 12. By locating the letter "N" on the innermost or code series of letters, the recipient will readily ascertain that the corresponding letter on the outer or clear text series is "A" and, hence, "A" will constitute the third letter of the decoded message. The operation of decoding or deciphering the message is completed by repeated depression of operating lever 43 and by translating the letters of the message from the code or cipher text to the clear text in the manner above described. When such translation is

completed, the actual decoded or deciphered message will read "Claims Allowed".

The methods of coding and decoding messages in the mechanisms shown in Figs. 11 to 14, inclusive, and in Figs. 15 to 21 inclusive, are substantially the same as those described in connection with Figs. 1 to 10, inclusive, the important difference in the constructions involved being restricted, essentially, to the mechanism which limits or restricts the return movement of the disc 22 and its associated parts and which thus determines the extent of the movement of arm 23 and hence the extent of rotation of the ratchet 30 and disc 33. In Figs. 1 to 19, inclusive, the variously-positioned and variously-dimensioned stop surfaces or shoulders are arranged on vertically-disposed discs 58, 59, 60 and 64, whereas in Figs. 11 to 14, inclusive, the stop surfaces or shoulders are arranged on horizontally disposed discs 97 and 100 mounted on vertical shaft 87, the disc 97 corresponding in function and operation to the disc 64, and the disc 100 corresponding in function and operation to the discs 58, 59 and 60. In Figs. 15 to 21, inclusive, the variously-positioned and variously-dimensioned stop surfaces are arranged on horizontally disposed discs 97', 117, 118 and 119, it being apparent that discs 97', 117, 118 and 119 correspond in function and operation to discs 64, 58, 59 and 60, respectively.

In all forms of the invention, the various discs and the variously toothed ratchets which drive these discs so limit or restrict the return or clockwise movement of disc 22, its arms 23 and 24 and its pawl 26, that the counterclockwise movement or "throw" imparted to said disc upon successive depressions or movements of the operating lever, is constantly varied to effect, to a very great extent, the successive and progressive movement of one set or sets of the text elements with respect to the other set or sets. The relationship of the various discs on their respective shafts, and the relationship of the various discs to each other, may be readily varied or changed to provide further variations in the extent of the successive movements or rotary increments imparted to the lettered discs 33 and 41. The ratchets which drive the discs may be replaced or interchanged to effect a further variation in the progressive movement of discs 33 and 41. Discs 97 and 100 may be inverted on shaft 87 to thus effect variations in the order or sequence of the variable rotary increments imparted to discs 33 and 41, similar variations, but to a still greater extent, being possible by inverting the discs 97', 117, 118 and 119 on the shaft 87'. Discs, such as 58, 59, 60, 64, 97, 97', 100, 117, 118 and 119 may be made up in sets in which the stop surfaces or shoulders are variously arranged and variously dimensioned, and by substituting one or more of these discs for one or more of the discs previously used, an exceedingly great number of different combinations are readily obtainable. The position of the disc 33 with respect to the ratchet 30 may be readily varied by removing the pin 34 from one of the holes 31 of the series in ratchet 30, rotating the said disc with respect to said ratchet, and inserting pin 34 in one of the other holes 31 of said series. The provision of one or more blank teeth 32 on ratchet 30 also assists in obtaining the varied movements of the several sets of text elements, it being obvious that when the nose of pawl 26 rests on the blank tooth or teeth 32, said pawl will slide along the surface of said tooth without imparting rotation to ratchet 30 or the

parts carried thereby during the initial movement of arm 23 and its pawl 26. Of course it is essential that the parts of each of the machines used for coding and decoding the messages be identically constructed and arranged, i. e., the machine used by the person decoding or deciphering the message must have its parts constructed and arranged in the identical manner as the machine used by the person coding the message. When such machines are so constructed and arranged and the several indicating marks are properly registered, successive actuation of the operating lever will effect identical movements of the lettered discs, and, hence, identical movements of the text elements.

It will thus be seen that I have provided a cryptographic machine by means of which an exceedingly great number of messages or the like may be coded and decoded without repetition of any particular code setting, thus insuring the secrecy of such messages and rendering it practically impossible to decode the message without the possession of a similarly constructed and arranged machine and without a prior knowledge of the setting of the machine at the time the message was coded. I have also provided a novel and efficient means for successively and progressively varying the extent of movement of a movable set or sets of text elements with respect to a fixed set of text elements whereby an exceedingly great number of relationships may be obtained between the fixed and movable sets of elements of the clear and code or cipher text.

It is to be understood that the forms of my invention shown and described herein are to be taken as preferred examples of the same, and that various changes in the shape, size and arrangements of parts may be resorted to without departing from the spirit of my invention or from the scope of the subjoined claims. The various mechanisms entering into the construction of my machine are susceptible of considerable variation and while the several forms of my invention shown and described herein constitute the preferred forms, it will be readily apparent that one skilled in the art may effect a considerable variation or modification of these several mechanisms without departing from the scope of the claims presented herein.

Having thus described my invention, what I claim as new and desire to secure by Letters Patent is:

1. A cryptographic machine including a casing having a cover provided with an opening, a series of stationary spaced tabs extending into said opening, each of said tabs having a letter on its upper surface, a first member below said cover having a first and a second series of letters on its upper surface with alternate letters of said first series visible between said tabs, a second member above said first member and having a series of spaced tabs each having a letter on its upper surface with the tabs of said second member overlying alternate letters of the second series on said first member, and means for moving said first and second members with respect to each other and with respect to the stationary tabs.

2. A cryptographic machine including a casing having a cover provided with a semi-circular opening, a series of spaced tabs on said cover and extending into said opening, each of said tabs having a letter on its upper surface, a first disc below said cover having two series of concentrically arranged letters on its upper surface with

alternate letters of the outermost of said series visible between said tabs, a second disc above said first disc and having a series of spaced tabs each having a letter on its upper surface with the tabs on said second disc overlying alternate letters of the innermost series of letters on said first disc, and means for rotating said first and second discs with respect to each other and with respect to the tabs on said cover.

3. A cryptographic machine including a casing having a cover provided with an opening, a series of stationary, spaced tabs extending into said opening, each of said tabs having a letter on its upper surface, a first member below said cover having a first and a second series of letters on its upper surface with alternate letters of said first series visible between said tabs, a second member above said first member and having a series of spaced tabs each having a letter on its upper surface with the tabs of said second member overlying alternate letters of the second series on said first member, means for moving said first member with respect to the stationary tabs to vary the relationship between the letters on said tabs and the letters of said first series on said first member, and means for moving said second member with respect to the first member and to the stationary tabs to vary the relationships between the letters on the tabs on said second member and the letters of the first and second series on said first member, and between the stationary tabs and the tabs on said second member.

4. A cryptographic machine including a casing having a cover provided with a semi-circular opening, a series of spaced tabs on said cover and extending into said opening, each of said tabs having a letter on its upper surface, a first disc below said cover having two series of concentrically arranged letters on its upper surface with alternate letters of the outermost of said series visible between said tabs, a second disc above said first disc and having a series of spaced tabs each having a letter on its upper surface with the tabs on said second disc overlying alternate letters of the innermost series of letters on said first disc, means for rotating said first disc with respect to the tabs on said cover to vary the relationship between the letters on said tabs and the letters of the outermost series on said first disc, and means for rotating said second disc with respect to the first disc and to the tabs on said cover to vary the relationships between the letters on the tabs on said second disc and the letters of the innermost and outermost series of letters on said first disc, and between the tabs on said cover and the tabs on said second disc.

5. A cryptographic machine including a casing having a cover provided with an opening, a series of stationary, spaced tabs extending into said opening, each of said tabs having a letter on its upper surface, a first member below said cover having a first and a second series of letters on its upper surface with alternate letters of said first series visible between said tabs, a second member above said first member and having a series of spaced tabs each having a letter on its upper surface with the tabs of said second member overlying alternate letters of the second series on said first member, means for imparting to said first member progressive, step-by-step movements of varying extent with respect to the stationary tabs to vary the relationship between the letters on said tabs and the letters of said first series on said first member, and means for imparting to said second member progressive step-by-step

movements with respect to the first member and to the stationary tabs to vary the relationships between the letters on the tabs on said second member and the letters of the first and second series on said first member, and between the stationary tabs and the tabs on said second member.

6. A cryptographic machine including a casing having a cover provided with a semi-circular opening, a series of spaced tabs on said cover and extending into said opening, each of said tabs having a letter on its upper surface, a first disc below said cover having two series of concentrically arranged letters on its upper surface with alternate letters of the outermost of said series visible between said tabs, a second disc above said first disc and having a series of spaced tabs each having a letter on its upper surface with the tabs on said second disc overlying alternate letters of the innermost series of letters on said first disc, means for rotating said first disc with respect to the series of spaced tabs on said cover by progressive, step-by-step rotary increments of successively varying extent to vary the relationship between the letters on said tabs and the letters of the outermost series on said first disc, and means for rotating said second disc with respect to the first disc and to the tabs on said cover by progressive, step-by-step rotary increments to vary the relationships between the letters on the tabs on said second disc and the letters of the two concentrically arranged series of letters on said first discs, and between the tabs on said cover and the tabs on said second disc.

7. A cryptographic machine comprising a series 35 of spaced, stationary tabs each having a letter on the upper surface thereof, a first disc mounted for rotation below said tabs and having on its upper surface an inner and an outer series of letters with alternate letters of said outer series 40 visible between said tabs, a first ratchet for rotating said first disc, a second disc mounted for rotation above said first disc and having a series of tabs each having a letter on its upper surface with alternate letters of said inner series of 45 letters on said first disc visible between said tabs, a second ratchet for rotating said second disc, means for imparting to said first ratchet progressive, step-by-step movements of varying extent to vary the relationship between the letters 50 on the stationary tabs and the letters of the outermost series of letters on said first disc, and means for imparting to said second ratchet progressive, step-by-step movements to vary the relationships between the letters on the tabs on said second disc and the letters of the series of letters 55 on said first disc, and between the stationary tabs and the tabs on said second disc.

8. A cryptographic machine comprising an ar- 60 cuate series of spaced, stationary tabs each hav- ing a letter on the upper surface thereof, a first disc mounted for rotation below said tabs and having on its upper surface an inner and an outer concentric series of letters with alternate letters of said outer series visible between said tabs, a first ratchet for rotating said first disc, a second disc mounted for rotation above said first disc and having a series of tabs each having a letter on its upper surface with alternate letters of said inner series of letters on said first disc 65 visible between said tabs, a second ratchet for rotating said second disc, an operating lever for imparting to said first ratchet progressive, step- 70 by-step movements of varying extent, and an operating lever for imparting to said second ratchet progressive, step-by-step movements.

9. A cryptographic machine comprising an arcuate series of spaced, stationary tabs each having a letter on the upper surface thereof, a first disc mounted for rotation below said tabs and having on its upper surface an inner and an outer concentric series of letters with alternate letters of said outer series visible between said tabs, a first ratchet for rotating said first disc, a second disc mounted for rotation above said first disc and having a series of tabs each having a letter on its upper surface with alternate letters of said inner series of letters on said first disc visible between said tabs, a second ratchet for rotating said second disc, a first operating lever having a pawl thereon engaging the first ratchet, means for actuating said first lever to impart thereto and to the ratchet driven thereby progressive step-by-step movements of varying extent to progressively, but to a varying degree, change the relationship between the letters of the inner and outer concentric series of letters and said tabs, a second operating lever having a pawl thereon engaging the second ratchet, and means for actuating said second lever to impart thereto and to the ratchet driven thereby progressive step-by-step movements to progressively vary the relationships between the letters on the tabs on said second disc and the letters of the concentric series of letters on said first disc, and between the stationary tabs and the tabs on said second disc.

10. A cryptographic member comprising an arcuate series of spaced, stationary tabs each having a letter on the upper surface thereof, a first disc mounted for rotation below said tabs and having on its upper surface an inner and an outer concentric series of letters with alternate letters of said outer series visible between said tabs, a first ratchet for rotating said first disc, a second disc mounted for rotation above said first disc and having a series of tabs each having a letter on its upper surface with alternate letters of said inner series of letters on said first disc visible between said tabs, a second ratchet for rotating said second disc, a first operating lever having a pawl thereon engaging the first ratchet, means for actuating said first lever to impart thereto and to the ratchet driven thereby progressive step-by-step movements of varying extent to progressively, but to a varying degree, change the relationship between the letters of the inner and outer concentric series of letters and said tabs, a second operating lever having a pawl thereon engaging the second ratchet, and means for actuating said second lever to impart thereto and to the ratchet driven thereby progressive step-by-step movements to progressively vary the relationships between the letters on the tabs on said second disc and the letters of the concentric series of letters on said first disc, and between the stationary tabs and the tabs on said second disc, actuation of said first operating lever effecting actuation of said second operating lever upon actuation of said machine.

11. A cryptographic machine comprising a first member having indicia thereon constituting a first series of letters, a second member having indicia thereon constituting a second series of letters disposed adjacent said first series and movable with respect to at least some of the letters of said first series, a lever for moving said second member and its series of letters, means for limiting the movement of said lever in a direction to effect movement of said second member and its series of letters, and means for progressively

varying the extent of movement of said lever in a reverse direction after movement of said second member and its series of letters by said lever to determine the extent of movement of said lever in said first mentioned direction until such movement is arrested by said limiting means, whereby the extent of movement imparted to said second member and its series of letters by said lever as it moves in said first mentioned direction is progressively varied upon successive actuations of said lever.

12. A cryptographic machine comprising a first member having indicia thereon constituting a first circular series of letters, a second member having indicia thereon constituting a second circular series of letters concentrically arranged with respect to said first series and adjacent thereto and including letters which are movable with respect to at least some of the letters of said first series, an oscillating lever for moving said second member and its series of letters, means for limiting the movement of said lever in a direction to effect rotation of said second member and its series of letters, and means for progressively varying the extent of movement of said lever in a reverse direction after movement of said second member and its series of letters by said lever to determine the extent of movement of said lever in said first mentioned direction until such movement is arrested by said limiting means, whereby the extent of movement imparted to said second member and its series of letters by said lever as it moves in said first mentioned direction is progressively varied upon successive actuations of said lever.

13. A cryptographic machine comprising a first member having indicia thereon constituting a first circular series of letters, a second member having indicia thereon constituting a second circular series of letters concentrically arranged with respect to said first series and adjacent thereto and including letters which are movable with respect to at least some of the letters of said first series, a ratchet for operating said second member and its series of letters, an oscillating lever having a pawl thereon for engaging said ratchet to move said ratchet and said second member and its series of letters during movement of said lever in one direction, means for limiting the movement of said lever in said one direction, and means for progressively varying the extent of movement of said lever and pawl in a reverse direction after movement of said second member and its series of letters by actuation of said lever in said one direction to determine the extent of movement imparted to said ratchet by said pawl and lever upon successive actuations of said lever in said one direction.

14. A cryptographic machine including a casing having a cover provided with an opening, a series of stationary tabs extending into said opening, each of said tabs having a letter on its upper surface, a first member below said cover having a first and second series of letters on its upper surface with alternate letters of said first series visible between said tabs, a second member above said first member and having a series of spaced tabs each having a letter on its upper surface with the tabs of said second member overlying alternate letters of the second series on said first member, a first lever for moving said first member with respect to the stationary tabs, a second lever for moving said second member with respect to the first member and with respect to the sta-

tionary tabs, and a common operating lever for actuating said first and second levers.

15. A cryptographic machine comprising a first member having indicia thereon constituting a first series of letters, a second member having indicia thereon constituting a second series of letters disposed adjacent said first series and movable with respect to at least some of the letters of said first series, a lever for moving said second member and its series of letters, means for limiting the movement of said lever in a direction to effect movement of said second member and its series of letters, a plurality of variously-positioned stop surfaces each adapted to be positioned in the path of movement of said lever for contact by said lever during reverse movement thereof after said lever has been moved in said first mentioned direction and such movement has been arrested by said limiting means, and means for successively presenting said stop surfaces in the path of the lever during said reverse movement for contact by said lever to successively and progressively vary the extent of movement of said lever in said reverse direction and to consequently vary the extent of movement of said lever during the next actuation thereof in said first mentioned direction.

16. A cryptographic machine comprising a first member having indicia thereon constituting a first series of letters, a second member having indicia thereon constituting a second series of letters disposed adjacent said first series and movable with respect to at least some of the letters of said first series, an oscillating lever for moving said second member and its series of letters, means for limiting the movement of said lever in a direction to effect movement of said second member and its series of letters, an arm carried by said lever and movable therewith, discs rotatably mounted adjacent said lever and each having thereon a plurality of variously-positioned stop surfaces each adapted to be positioned in the path of movement of said arm for contact by said arm during reverse movement thereof after said lever has been moved in said first-mentioned direction and such movement has been arrested by said limiting means, and means for imparting to said discs a progressive, step-by-step rotation during the movement of said lever in said first mentioned direction to successively present said stop surfaces in the path of the arm during said reverse movement for contact by said arm to successively and progressively vary the extent of movement of said lever during the next actuation thereof in said first mentioned direction.

17. A cryptographic machine comprising a first member having indicia thereon constituting a first series of letters, a second member having indicia thereon constituting a second series of letters disposed adjacent said first series and movable with respect to at least some of the letters of said first series, an oscillating lever for moving said second member and its series of letters, means for limiting the movement of said lever in a direction to effect movement of said second member and its series of letters, an arm carried by said lever and movable therewith, a shaft adjacent said lever and arm, separate discs rotatably mounted on said shaft and each having thereon a plurality of variously-positioned stop surfaces each adapted to be positioned in the path of movement of said arm for contact by said arm during its reverse movement after the lever has been moved in said first mentioned direction and such movement has been arrested by said limit-

ing means, means for rotating said discs on said shaft to successively present the stop surfaces on said discs in the path of the arm during said reverse movement for contact by said arm to successively and progressively vary the extent of movement of said lever during its next actuation in said first mentioned direction, and means for oscillating said lever.

18. A cryptographic machine as claimed in claim 17, in which the separate discs are rotated on the shaft by rotary increments of different extents to thereby effect differential rotation of said discs and to relatively vary the successive positions of the stop surfaces thereon for contact by the arm on the lever.

19. A cryptographic machine as claimed in claim 17 in which some of the discs are keyed together for simultaneous rotation on said shaft by rotary increments imparted thereto, and in which at least one of the other of said discs is rotated on said shaft by rotary increments of an extent different from the rotary increments imparted to said first mentioned discs.

20. A cryptographic machine comprising a first member having indicia thereon constituting a first series of letters, a second member having indicia thereon constituting a second series of letters disposed adjacent said first series and movable with respect to at least some of the letters of said first series, an oscillating lever for moving said second member and its series of letters, means for limiting the movement of said lever in a direction to effect movement of said second member and its series of letters, an arm carried by said lever and movable therewith, a shaft adjacent said lever and arm, separate discs rotatably mounted on said shaft, a first ratchet rotatably mounted on said shaft having a predetermined number of teeth and connected to at least one of the discs on said shaft, a second ratchet rotatably mounted on said shaft having a number of teeth different from the number of teeth on said first ratchet and connected to the remainder of discs on said shaft, each of said discs having thereon a plurality of variously-positioned stop surfaces each adapted to be positioned in the path of movement of said arm for contact by said arm during its reverse movement after the lever has been moved in said first mentioned direction and such movement has been arrested by said limiting means, means for imparting progressive step-by-step rotation to said ratchets and to the discs connected thereto to successively present the stop surfaces on said discs in the path of the arm during such reverse movement for contact by said arm to successively and progressively vary the extent of movement of said lever during its next actuation in said first mentioned direction, and means for oscillating said lever.

21. A cryptographic machine comprising a first member having indicia thereon constituting a first series of letters, a second member having indicia thereon constituting a second series of letters disposed adjacent said first series and movable with respect to at least some of the letters of said first series, an oscillating lever for moving said second member and its series of letters, an arm carried by said lever and movable therewith, a shaft adjacent said lever and arm, a first disc mounted on said shaft, a second disc mounted on said shaft adjacent said first disc, said discs having a plurality of variously-positioned stop surfaces adapted to be positioned in the path of movement of said arm for contact by said arm when the lever is moved in one direction, means

for rotating said discs on said shaft by rotary increments of different extents to thereby effect differential rotation of said discs on said shaft to successively vary the successive positions of the stop surfaces on said discs for contact by the arm on the lever when said lever and arm are moved in said one direction, contact between said arm and said stop surfaces determining the extent of movement of said lever in an opposite direction to thereby successively vary the extent of movement of said second member and its series of letters

with respect to said first member and its series of letters, and means for oscillating said lever.

22. A cryptographic machine as claimed in claim 7 in which means are provided for varying the relative position between the first disc and its associated ratchet.

23. A cryptographic machine as claimed in claim 20 in which means are provided for varying the relative positions of the discs with respect to their associated ratchets.
